UNITED STATES PATENT OFFICE.

IRVING H. ATWOOD, OF AMESBURY, MASSACHUSETTS.

DESIGN FOR A LAMP.

No. 37,772.

Specification for Design.

Patented Jan. 2, 1906.

Application filed November 28, 1905. Serial No. 289,541. Term of patent 7 years.

To all whom it may concern:

Be it known that I, IRVING H. ATWOOD, a citizen of the United States, and a resident of Amesbury, Essex county, State of Massachusetts, have invented a new, original, and ornamental Design for Lamps, of which the following is a specification, reference being had to the accompanying drawings, forming a part thereof.

Figure 1 is a perspective view of a lamp, showing my design; and Fig. 2 is a perspective view of the same, taken from the rear.

What I claim is—

The ornamental design for a lamp as shown.

IRVING H. ATWOOD.
